BELT MOUNTED MASSAGING DEVICE

Samuel L. McNair, Overland Park, Kans., assignor to
Dazey Products Co., Kansas City, Mo.

Filed June 20, 1973, Ser. No. 371,735

Term of patent 14 years

Int. Cl. D28—03

U.S. Cl. D83—1 S

Fig. 1.

Fig. 2.

Fig. 3.

Fig. 4.

Fig. 5.

FIG. 1 is a perspective view of a belt mounted massaging device showing my new design;

FIG. 2 is a frontal view on a large scale of same;

FIG. 3 is a side elevational view of same taken from the left hand side of FIG. 2; the right hand side is substantially the same in appearance;

FIG. 4 is a bottom view taken from the bottom of FIG. 2; the top plan view is substantially the same in appearance; and

FIG. 5 is a fragmentary sectional view taken generally along line 5—5 of FIG. 2 in the direction of the arrows.

I claim:

The ornamental design for a belt mounted massaging device, as shown and described.
